COFFEE MAKER

Leonard P. Hausam, 5801 50th Ave. N.,
Minneapolis, Minn. 55424

Filed July 17, 1967, Ser. No. 7,837

Term of patent 14 years

(Cl. D94—3)

FIG. 1 is a front perspective view of a coffee maker embodying my new design;

FIG. 2 is a side elevation of the coffee maker;

FIG. 3 is a front elevation of the coffee maker;

FIG. 4 is a top plan view of the coffee maker.

The rear of the coffee maker is substantially flat and plain in appearance. The broken line showing of the container is depicted for illustrative purposes only.

I claim:

The ornamental design for a coffee maker, substantially as shown and described.
